SOCK DRIER

Lillian M. Lake, Manhattan Beach, Calif.

Application April 17, 1950, Serial No. 156,361

7 Claims. (Cl. 223—77)

1

This invention relates to a device for holding men's wool socks and the like in proper shape while the socks are drying after being washed. Sock driers, or sock stretchers, as they are known in the art, are commonly used to prevent excessive shrinkage of wool socks and the like while they are being dried. Such devices are commonly formed in a single plane such as, for example, as shown in the Kerbaway patent, Re. 22,862. Men's wool socks dried on such a device do not take the shape of a human foot but are stretched out of natural position.

It is the principal object of this invention to provide an improved form of sock drier which holds the drying sock in the shape of a human foot and which provides for free passage of air for drying.

Another object of this invention is to provide an adjustable device of this type in which a foot portion may be adjusted relative to an ankle portion to accommodate socks of different sizes.

A more detailed object is to provide a sock drying shell of hollow formation in the general form of a human foot and ankle, which shell is provided with a large number of apertures over its entire surface, the shell being formed of an ankle portion and a telescopic foot portion which are relatively adjustable to accommodate socks of different sizes, the increments of adjustment corresponding to the aperture spacing so that the apertures in the two portions remain in registry.

Other objects and advantages will be described more fully hereinafter.

In the drawings:

Figure 1 is a perspective view showing a preferred form of my invention, a number of the apertures being omitted for clarity of illustration.

Figure 2 is a longitudinal sectional view taken substantially on the lines 2—2 as shown in Figure 1.

Figure 3 is a transverse sectional elevation taken substantially on the lines 3—3 as shown in Figure 2.

Referring to the drawings, I provide a hollow shell 10 formed in the shape of a human foot and ankle. This shell is preferably constructed of light-gauge metal, although it may be formed of plastic or other materials if desired. The shell is of two part construction including an ankle piece 11 and a foot piece 12. One end of the foot piece 12 is received in telescopic relation within the ankle piece 11. As shown in the drawings, the lower side surfaces 13 on the ankle piece 11 are curved to provide parallel guides for reception of the rearwardly extending projection 14 formed integrally on the foot piece 12. The projection 14 is oval in cross-section and slidably mounted within the guides thus formed by the curved surfaces 13, and hence the foot piece 12 is telescopi-

cally received within the lower part of the ankle piece 11.

A central strip 15 is cut from the bottom of the ankle piece 11, and is folded back as shown at 16 against the heel portion of the ankle piece 11. This strip is bent forwardly as shown at 17 and extends horizontally across the hollow interior thereof toward the extreme forward end 18 of the ankle piece 11. At its forward end the strip 15 is bent back to form a tab 19, and this tab may be secured to the adjacent portion of the ankle piece 11 by any convenient means such as, for example, by spot welding 20. The horizontal portion 21 of this strip 15 contacts the upper surface 22 of the projection 14 in sliding relationship. The foot piece 12 is thus guided for sliding movement into and out of the socket 23 in the lower end of the ankle piece 11 but is prevented from turning with respect thereto by reason of its oval cross-section and the guides provided by the surfaces 13 and the horizontal portion 21 of the strip 15.

In order to provide maximum drying effect the shell 10 is provided with a large number of closely spaced apertures 24. These apertures have been largely omitted in Figure 1 for clarity of illustration. The apertures 24 are provided in both the ankle piece 11 and the foot piece 12 so that maximum drying effect may be obtained.

Means are provided for adjustably securing the foot piece 12 relative to the ankle piece 11 in any one of a plurality of positions in order that the single drier shell 10 may be used to dry socks of different sizes. As shown in the drawings, this 30 means may include a spring element 25 fixed at one end within the interior of the oval projection 14 by any convenient means such as, for example, by spot welding 26. This element 25 may be shaped at its extending end to provide a handle 27. A latch pin 28 fixed to the spring element 25 projects through an aperture 29 in the oval projection 14 and extends into any one of a plurality of latch openings 30 provided in the horizontal piece 21. The spacing of the latch openings 30 is chosen as a multiple of the horizontal spacing of the apertures 24 in the projection 14 and surfaces 13 so that the inner and outer apertures are in registry when the latch pin 28 is received within any one of the latch openings 30.

The bottom of the form 10 is open to permit access of the fingers of the user into the interior of the oval shaped projection 14 and into the interior of the lower portion of the ankle piece 11. As shown clearly in Figure 3, this opening 31 is defined between the parallel edges 32 on the oval projection 14 and between the parallel edges 33 on the ankle piece 11 formed by cut-out of the strip 15. The latching device, including the spring element 25, handle 27, pin 28 and latch openings 30, is mounted in an out of the way

location and yet is easily accessible through the lower opening.

The upper end 34 of the ankle piece 11 may be reduced in size as shown to correspond with the location of ribbing customarily provided at the upper end of men's wool socks. A support clip 35 may extend upwardly from the reduced portion 34 and provided with a hook 36 so that the shell 10 and an enveloping sock may be suspended from any convenient support.

If desired, a scale may be provided on the under surface 37 of the foot piece 12. The forward edge 18 of the ankle piece 11 may then be used as an index with this scale so that the user may select the proper adjusted position for the foot piece 12 relative to the ankle piece 11 to correspond with any nominal size of men's socks within the range of adjustment.

Having fully described my invention, it is to be understood that I do not wish to be limited to the details herein set forth, but my invention is of the full scope of the appended claims.

I claim:

1. In a sock drier, the combination of: a hollow ankle member, a hollow foot member adjustably mounted thereon for sliding movement, the foot member and ankle member being shaped to simulate a human foot, ankle and lower leg, the foot member and ankle member each being provided with a large number of apertures distributed over substantially the entire surface of said members, and means including a releasable positive latch device for adjustably securing the foot member to the ankle member at a plurality of positions spaced in even multiples of the spacing of the apertures, so that apertures in overlapping portions of said members remain in registry.

2. In a sock drier, the combination of: a hollow ankle member, a hollow foot member adjustably mounted thereon for sliding movement, the foot member and ankle member being shaped to simulate a human foot, ankle and lower leg, the foot member and ankle member each being provided with a large number of apertures distributed over substantially the entire surface of said members, and means including a releasable positive latch device within said members for adjustably securing the foot member to the ankle member at a plurality of positions spaced in even multiples of the spacing of the apertures, so that apertures in overlapping portions of said members remain in registry.

3. In a sock drier, the combination of: a hollow ankle member, a hollow foot member telescopically mounted therein for sliding movement, the foot member and ankle member being shaped to simulate a human foot, ankle and lower leg, the foot member and ankle member each being provided with a large number of apertures distributed over substantially the entire surface of said members, and releasable positive latch means within said members for adjustably securing the foot member to the ankle member at a plurality of equally spaced positions, the apertures in the telescoping portions of said members being spaced so that they register at each of said positions.

4. In a sock drier, the combination of: a two-part hollow form shaped to simulate a human foot, ankle and lower leg, the form including an ankle member and a foot member, cooperating sliding parts on the members providing an adjustable mounting for the foot member on the

ankle member, said cooperating parts permitting movement of the foot member in a direction lengthwise of the foot member, a positive latch device positioned within the interior of said form for securing the foot member to the ankle member at a plurality of positions, the foot member having an access opening extending along its lower portion so that the latch device may be manually operated.

5. In a sock drier, the combination of: a two-part hollow form shaped to simulate a human foot, ankle and lower leg, the form including an ankle member and a foot member, cooperating sliding parts on the members providing a telescopic mounting for the foot member within the ankle member, said cooperating parts including a projection on the foot member received within a socket on the ankle member and permitting movement of the foot member in a direction lengthwise of the foot member, a positive latch device positioned within the interior of said form for securing the foot member to the ankle member at a plurality of positions, said members having an access opening along the lower portion of each so that the latch device may be manually operated.

6. In a sock drier, the combination of: a two-part hollow form shaped to simulate a human foot, ankle and lower leg, the form including an ankle member and a foot member, cooperating sliding parts on the members providing an adjustable mounting for the foot member on the ankle member, said cooperating parts permitting movement of the foot member in a direction lengthwise of the foot member, a positive latch device positioned within the interior of said form for securing the foot member to the ankle member at a plurality of positions, the foot member having an access opening extending along its lower portion so that the latch device may be manually operated, said members each being provided with apertures distributed over substantially the entire surface of said members, the apertures in the telescoping portions of said members being spaced so that they register at each of said positions of the foot member.

7. In a sock drier, the combination of: a two-part hollow form shaped to simulate a human foot, ankle and lower leg, the form including an ankle member and a foot member, a projection on the foot member slidably received within the ankle member so that movement of the foot member in a lengthwise direction is permitted, a strip of the lower portion of the ankle member being removed to provide an access opening for the interior of the form, the strip being doubled back within the ankle member and extended forwardly to provide a horizontal guide for the projection on the foot member, and a latch device positioned within the interior of said form for securing the foot member projection to the ankle member guide at a plurality of positions.

LILLIAN M. LAKE.
